UNITED STATES PATENT OFFICE.

JOHN J. REINHOLD, OF MARIETTA, PENNSYLVANIA.

DOOR CLOSER.

Application filed May 21, 1923, Serial No. 640,507.

To all whom it may concern:

Be it known that I, JOHN J. REINHOLD, a citizen of the United States, residing at Marietta, in the county of Lancaster and 5 State of Pennsylvania, have invented new and useful Improvements in Door Closers, of which the following is a specification.

This invention relates to door closing devices. The object of this invention is to 10 incorporate an adjustable stopping device, which will limit the closing movement of the door, in a door closing device having such characteristics wherein the door may be easily opened, and which will automatically 15 close the door at a moderate slow speed.

This invention will be more fully understood and other objects will be apparent from the following description, taken in 20 connection with the accompanying drawing, forming a part hereof, and in which similar numerals refer to similar parts throughout the several views.

Fig. 1, is a side elevation of a door closing 25 device with my adjustable stopping device incorporated.

Fig. 2, is a plan view of Fig. 1.

Fig. 3, is a sectional view taken on line 3-3 of Fig. 2.

30 Fig. 4, is a bottom view of the latch carrying bracket 4, of Figs. 1, 2 and 3.

Fig. 5, is a detail drawing of the segmental rack 5, of Figs. 1, 2, 3 and 4; two views being represented.

35 This invention will be described and shown herein as applied specifically to a door closing device of that type known as the "Yale reversible door closer". It will be obvious that the general principles are 40 applicable to various other door closing devices of similar character.

Briefly describing the pertinent features 45 of the door closer shown in the drawing, it is to be understood that the bowl 6 contains a spring which normally holds the ratchet 7 at a neutral position, and any turning of this ratchet in either direction from this neutral position can be accomplished only against the action of this spring. The lever 50 10 is carried by the spindle 11 and is locked to the ratchet 7 through the pawl 12; therefore any movement of the lever 10 in the direction indicated by the arrow 14 must necessarily operate against the action of said 55 spring in the bowl 6. The bowl 6 is carried by the door 15 through the brackets 16 and

screws 17. The end 18 of the lever 10 is connected to the door frame 19 through the link 20, bracket 21 and screws 22.

Now if the door 15 is swung on the hinge 23 in the direction indicated by the arrow 24, the bowl 6 will move through a path indicated by the arc 25. The link 20 will prevent the lever end 18 from moving with the door and will therefore cause a turning 60 movement of the lever 10 relative to the bowl 6. This turning movement will cause a winding up of said spring in the bowl 6 with the result that when the door is released it will automatically close, and ordinarily with a slam. To avoid slamming of the door the spindle 11 is governed by suitable means within the bowl 6, which permits rapid turning thereof when the door is being opened, but when the door is being 65 closed the movement of the lever 10 is restricted to a moderate slow speed.

The foregoing description relative to the Yale reversible door closer is matter which is old and well understood by those experienced in the operation of door closing 70 devices.

My object being to provide an adjustable stop to limit the closing movement of the door, I therefore provide a segmental rack 85 5 which is carried by the spindle 11, the same being locked against turning relative thereto through the flat sides 26 of the hole 27, these flat sides fitting corresponding flat sides 28 on the spindle 11. The segmental 90 rack 5 is provided with a hub 29 upon which is fitted free to turn the lever 10 and latch carrying bracket 4. The segmental rack 5 is also provided with lugs 30 and 31, which are adapted to contact with the lug 32 forming part of the bowl lid 33. The lug 30 limits the turning movement of the segmental rack 5 in the direction indicated by the arrow 45. The lug 31 limits the turning 100 movement of the segmental rack 5 in the direction opposite to that indicated by the arrow 45, however this lug 31 is of no use when the door closing device is mounted to a door which is hinged as shown in Fig. 2, or specifically a right-hand door. When the door closing device is mounted on a left-hand door, then the segmental rack 5 including the spindle 11 is turned until the lug 31 contacts with the lug 32, and the other elements of the door closing device are 105 arranged in the proper and well known order for operating the left-hand door. Under

these conditions the lug 30 is of no use while the lug 31 limits the turning movement of the segmental rack 5.

To the latch carrying bracket 4 is pivoted a latch 34 through the pin 35, this latch is adapted to engage between the teeth 36 of the segmental rack, and latch the same against turning movement relative to the latch carrying bracket 4. A spring 37 normally holds the latch 34 in engagement with the teeth 36. A cord 38 is attached to the latch 34 and carries a ring 39. It is obvious that by pulling the cord 38 the latch 34 may be disengaged with the teeth of the segmental rack 5. The guide pieces 40 form part of the latch carrying bracket 4 and guide the movement of the latch 34.

The lever 10 is provided with a radial groove 41 into which projects a lug 42 which forms part of the latch carrying bracket 4. This groove and lug permits a limited amount of movement of the lever 10 relative to the latch carrying bracket 4, however this limited movement does not interfere with the closing action imparted to the door through the operation of the door closing device. This feature is not new and is usually found on the standard Yale reversible door closer, and its functions are not altered by the incorporation of my adjustable stop.

The operation of this device is as follows:—With the latch 34 engaged with the segmental rack 5 as shown in the drawing, the door will be completely closed by the action of the door closer, the same acting in the usual manner. If it is desired that the closing movement of the door should be limited, the proper adjustment is made by pulling on the cord 38, thereby releasing the latch 34 from the segmental rack 5, and then move the door approximately to the position it is desired that it should stop. During this movement of the door the lever 10 and the latch carrying bracket 4 will turn on the hub 29, while the segmental rack 5 and the spindle 11 remains idle. Now by permitting the latch 34 to engage again with the segmental rack 5 the door is prevented from completely closing, because the lever 10 has changed its position relative to the segmental rack 5, and through the same being locked thereto in this changed position the lever 10 is limited in its turning movement in the direction indicated by the arrow 45. There is nothing to interfere with the opening movement of the door, for then the segmental rack 5 and the lever 10 turn together in the direction indicated by arrow 14; but the said spring contained in the bowl 6 will normally turn the lever 10 and segmen-

tal rack 5 in the direction indicated by the arrow 24 until the lug 30 contacts with the lug 32. It is apparent that various stopping positions are available as the latch 34 may be engaged between any of the various teeth 36.

To prevent the bowl cap 33 from turning relative to the bowl 6 from any strain caused by the lug 30 contacting with the lug 32, I provide a lug 43 which forms part of the bowl 6 and engages between the ears 44 of the bowl cap 33.

For changing this device to be used on a left-hand door, it is only necessary to release the pawl 12 and turn the lever 10 and segmental rack 5 including the spindle 11 in the direction indicated by the arrow 14 until the lug 31 contacts with the lug 32, and then engage the pawl 12 with the ratchet 7 on the opposite side of the lever. Otherwise this device is mounted in the usual manner.

Having thus described my invention, what I claim and desire to secure by Letters Patent is as follows:—

1. In an automatic door closing device, the combination of a casing, a rotatable spindle, a lever carried by said spindle and arranged to connect with the door, a spring actuated ratchet surrounding said spindle and arranged to turn said lever, a latch carrying bracket fixed to rotate with said spindle, means for fixing said latch carrying bracket to said lever, said fixing means being arranged to permit a slight turning movement of said lever relative to said bracket, a segmental rack fixed to said spindle, a stop arranged to limit turning movement of said segmental rack and thereby limit the closing movement of said door, and latching means arranged to lock said segmental rack to said lever at various points angularly around the axis of said spindle and thereby providing optional stopping points in the closing movement of said door.

2. The combination with a door closing device comprising a rotatable spindle, speed controlling means for said spindle, a rotatable sleeve, and resilient means arranged to react against turning movement of said sleeve; of a lever arranged to turn upon said spindle, means for locking said lever to said sleeve, a segmental rack fixed to rotate with said spindle, locking means arranged to connect said lever with said segmental rack at optional points angularly around the axis of said spindle, and a stop arranged to limit turning movement of said segmental rack.

In testimony whereof I affix my signature.

JOHN J. REINHOLD.
